SKI SLED

Albert J. Giannotti, Redwood City, Calif.

Application February 18, 1952, Serial No. 18,572

Term of patent 14 years

(Cl. D34—15)

To all whom it may concern:

Be it known that I, Albert J. Giannotti, a citizen of the United States, residing at Redwood City, State of California, have invented a new, original, and ornamental Design for Ski Sled, of which the following is a specification, reference being had to the accompanying drawing, forming a part hereof.

Fig. 1 is a top plan view of a ski sled, showing my new design.

Fig. 2 is a side elevational view of the ski sled of Fig. 1.

Fig. 3 is a front end elevation of the ski sled of Fig. 1.

I claim:

The ornamental design for a ski sled, as shown.

ALBERT J. GIANNOTTI.
